UNITED STATES PATENT OFFICE

LEON M. BELL, OF PORTSMOUTH, OHIO

PRESSED IN SPUT

Application filed August 18, 1931. Serial No. 557,930.

This invention relates to metallic drums, the primary object of the invention being to provide novel means for securing sputts in the sputt openings of drums, in such a way as to insure against the sputts moving or rotating within their openings, when excessive pressure is directed to the bungs in removing the bungs.

Another object of the invention is the provision of a sputt having lugs or bosses of a novel construction, so that the metal of the drum will be securely connected with the sputt, when the sheet metal of the drum is pressed into engagement with the lugs or bosses.

A still further object of the invention is the provision of a sputt constructed in such a manner that a sputt may be secured by a single pressing operation, while the metal of the drum is cold.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a sectional view through a sputt, constructed in accordance with the invention, illustrating the same as positioned within the sputt opening of a drum.

Figure 2 is a plan view of the sputt.

Figure 3 is a sectional view through the sputt and drum, taken through one of the lugs or bosses of the sputt.

Figure 4 is a sectional view through a sputt and drum, illustrating the machine used in pressing the sheet metal of the drum into engagement with the sputt.

Figure 5 is a modified form of sputt, showing the same as secured within the sputt opening of a drum.

Figure 6 is a sectional view through the modified form of the invention, the same being taken through one of the enlargements or bosses of the sputt.

Referring to the drawings in detail, the reference character 5 designates a metallic drum, constructed of sheet metal, the same being of the usual and well known construction.

The reference character 6 designates the sputt forming an important feature of the present invention, and as shown the sputt is provided with an annular rib 7, formed adjacent to its upper end, the outer upper edge of the rib being inclined as at 8.

Formed integral with the rib, and extending therefrom, are spaced enlargements or bosses 9, which present sharp corners, so that the sheet metal of the drum may be pressed into close engagement with the enlargements or bosses 9, the sharp corners forming depressions in the drum, locking the sputt to the drum in such a way as to insure against rotary movement of the sputt, should excessive pressure be directed to the sputt in an effort to remove the bung therefrom.

The bung is indicated by the reference character 10 and is screwed into the sputt in the usual and well known manner, there being provided a gasket between the flange 12 of the bung and drum, to provide a fluid tight connection between the bung and drum.

To further insure a fluid tight connection at the sputt, a substantially thin washer 13 is provided between the annular rib 7 and the inturned flange 14 of the drum.

As shown by Figures 5 and 6 of the drawings the drum is indicated by the reference character 15, and in this form of the invention, the sputt which is indicated by the reference character 16, is formed with an annular rib 17, the undersurface thereof being provided with a plurality of enlargements or bosses to be embedded in the sheet metal of the drum, during the pressing of the drum to secure the sputt.

In the positioning of the sputt, a machine is employed, such as indicated by Figure 4 of the drawings, the machine comprising a stationary former 19 which is provided with a bevelled surface 20 against which the metal of the drum, indicated at 21, is pressed. Carried by the former 19 is a former 22 which is substantially short, to receive the end of the

wall of the sput opening, the construction of the former being such that when properly positioned and the machine is operated, a portion of the drum adjacent to the sput opening, 5 will be inclined as shown at 23, leaving an upstanding portion 24 spaced from the upper edge of the former 19.

The machine also includes a presser head 25 that embodies a circular pressing member 26 10 formed with an inclined surface to engage the drum and force the same into engagement with the former 19.

Springs 27 are disposed between the pressing member 26 and presser head, so that when 15 the presser head moves downwardly, the pressing member 26 may contact with the drum forcing the drum into engagement with the former 19, so that further movement of the pressing member will permit the pressing member 20 to engage the upstanding portion 24 of the drum, bending it into engagement with the sput and gripping the drum around the enlargements 9.

From the foregoing it will be seen that due 25 to the construction shown and described, a sput may be securely fastened within the sput opening of a drum, to insure against rotary movement of the sput.

Having thus described the invention, what 30 is claimed is.

I claim:

1. The combination with a metallic shipping drum having a sput opening, of a sput fitted in the opening, said sput having an annular rib formed at the upper end thereof, 35 said annular rib having an inclined upper surface, enlargements formed on the inclined upper surface, said enlargements having vertical side surfaces and horizontal upper surfaces, the side and upper surfaces of the enlargements defining sharp corners at their meeting edges, the drum adapted to be pressed around the enlargements and the sharp corners biting into the drum locking 45 the sput within the opening.

2. The combination with the metallic shipping drum having a sput opening, of a sput fitted in the opening, an annular rib formed at the upper end of the sput, enlargements on the rib, said enlargements having sharp edges and adapted to cut into the drum pressed around the annular rib and enlargements, said annular rib presenting a horizontal lower surface over which the metal of 50 the drum is pressed, and the sput being of a length to extend an appreciable distance below the annular rib, and against which the metal of the drum engages.

60 In testimony that I claim the foregoing as my own, I have hereto affixed my signature.

LEON M. BELL.
